UNITED STATES PATENT OFFICE.

ROBERT V. BINGAY, OF PITTSBURGH, PENNSYLVANIA, ASSIGNOR TO PITTSBURGH TRANSFORMER COMPANY, A CORPORATION OF PENNSYLVANIA.

FILTER.

Application filed September 1, 1922. Serial No. 585,616.

To all whom it may concern:

Be it known that I, ROBERT V. BINGAY, a citizen of the United States, residing at Pittsburgh, in the county of Allegheny and 5 State of Pennsylvania, have invented certain new and useful Improvements in Filters, of which the following is a specification.

This invention relates to protective devices, and is of especial advantage for use in 10 transformers or other devices immersed in oil in a tank. Due to the alternate heating and cooling of the transformer in service the oil correspondingly expands and contracts 15 in volume and to permit this alternate expansion and contraction of the oil an air space is provided above it with a "breather" connection to the outside air. It is important to exclude moisture from entering 20 the transformer through this breather connection as such moisture impairs the insulating properties of the oil, and the general object of this invention is to provide a breather with moisture excluding means which is 25 simple and inexpensive in construction and of large capacity so that even under extremely wet conditions practically no moisture will enter the transformer.

In the breather connection of this invention 30 a mass of absorbent material acts to absorb any moisture so as to exclude it from the transformer. During the cooling of the transformer the entering air is required to traverse extended tortuous paths through the mass of the absorbent material and is 35 effectively dried thereby. Upon the next heating of the transformer the hot dry air driven out from the air space above the oil is forced in reverse direction through the 40 mass of absorbent material so as to thoroughly dry it and leave it in condition to absorb moisture again during the next cooling of the transformer. In this way the 45 heat of the transformer is used to exclude moisture from the transformer oil.

In the accompanying drawing the invention is illustrated by a vertical sectional view of a specific embodiment in which a transformer having a top 5 and oil 6 is provided with a breather B connecting the air space 7 above the oil 6 to the outside air.

The top 5 of the transformer is provided with an opening 8 in which is set a bushing 9 with a weld 10 in the corner between the bushing and the transformer top so as to

make the connection air-tight. Threaded into the bushing 9 is a vertical pipe 11 carrying a disc 12 welded to the pipe at 13 and having at its outer periphery downwardly bent lugs 14. The outer end of the pipe 11 60 extends above the disk 12 and is preferably provided with a screen or gauze 15 fastened in place by the cap ring 16. A semi-spherical cover member 17 is fastened at its edge portion to the lugs 14 by screws 18, an 65 annular opening being left between the cover 17 and the peripheral edge 20 of the disk 12.

A chamber is thus left between the top member 17 and the disk member 12 with the 70 top of the chamber opening downwardly through pipe 11 to the transformer air space and the bottom of the chamber opening downwardly through the annular space 19 to the air. Within this chamber a mass of 75 absorbent material 21 is packed so that the air in passing in or out of the transformer is forced to seep through this material which acts as a filtering, absorbent mass to withdraw the moisture from the entering air. 80

Upon cooling of the transformer and resultant drop of pressure in the air space 7 atmospheric pressure will force air up through the annular opening 19 and through the material 21 and down through the screen 85 15 and pipe 11. The absorbent material 21 may be glass-wool, that is, fine glass so fine that it is like cotton or it may be a mixture of asbestos or other absorbent material. In its passage through this material the air is 90 deprived of its moisture and enters pipe 11 free from moisture. The pipe opening to the transformer air space is positioned above the level of the annular opening 19 to the air and in such a manner that the air has to 95 traverse the entire mass of the absorbent material 21; and the cross section of the air passage through this material is very large in comparison with the cross section of the air passages through pipe 11 and opening 19. 100

The relative velocity of the air in passing through the mass of absorbent material is therefore low and the entering air passing upward slowly through this material remains a long time in contact therewith so as 105 to have its moisture thoroughly and effectively removed. Similarly the hot outgoing air during the heating of the transformer thoroughly dries out the absorbent mass so as to give a very effective self drying action. 110

The breather of this invention is simple and inexpensive in construction and small in size and at the same time provides a relatively large mass of absorbent material for the moisture excluding action. The cover member 17 is shaped to naturally shed rain and moisture and its overhanging edge forms a depending petticoat around the annular space 19. This cover member is also easily removed for inspection or replacement for the charge of absorbent material and all parts of the apparatus are easily accessible for repair. The absorbent material of this invention acting to physically filter the moisture from the air is advantageous over chemical absorbent agents, such as calcium chloride, in not permanently accumulating moisture, but by redelivering it to the outgoing air the drying means of this invention is automatically self-drying. Chemical agents for absorbing moisture require frequent removal and renewal and if left unchanged, as is usual, their accumulation of moisture becomes a source of wetting the entering air instead of drying it.

I claim:—

1. The combination with a tank containing a fluid and having an enclosed space permitting the fluid to expand and contract, of means for permitting the passage of air to and from said space comprising a chamber containing inert absorbent material adapted to physically filter moisture from the air.
2. The combination with a tank containing a fluid and having an enclosed space permitting the fluid to expand and contract, of means for permitting the passage of air to and from said space comprising a chamber containing a mass of absorbent material adapted to physically filter moisture from the entering moist air and to redeliver said moisture to the outgoing dry air.
3. The combination with a transformer tank containing a fluid and having an enclosed space permitting the fluid to expand and contract, of means for permitting the passage of air to and from said space comprising a chamber containing a mass of absorbent material adapted to physically filter moisture from the air, said chamber having an opening to said tank and a separate opening to the air.
4. The combination with a transformer tank containing a fluid and having an enclosed space permitting the fluid to expand and contract, of means for permitting the passage of air to and from said space com-

prising a chamber containing a mass of absorbent material adapted to physically filter moisture from the air, said chamber having an upper opening to said tank and a separate lower opening to the air.

5. The combination with a transformer tank containing a fluid and having an enclosed space permitting the fluid to expand and contract, of means for permitting the passage of air to and from said space comprising a chamber containing a mass of fibrous absorbent material adapted to physically filter moisture from the air.

6. The combination with a receptacle of means for permitting the passage of air to and from said tank, and a mass of absorbent material in said passage adapted to physically filter moisture from the air, and itself exposed to the air and adapted to give up moisture to the air under some conditions.

7. The combination with a tank containing a fluid and an enclosed space permitting the fluid to expand and contract, of means for permitting a passage of air to and from said space comprising a pipe extending outwardly from said tank, a dome shaped member spaced from the outer end of said pipe and forming a wall of a chamber, material adapted to absorb moisture from the air located in said chamber and in the path of the air leaving or entering the outer end of said pipe.

8. The combination with a tank containing a fluid and having an enclosed space permitting the fluid to expand and contract, of means for permitting the passage of air to and from said space comprising a pipe extending upwardly from said tank, a plate secured to said tank intermediate the ends of said pipe and a member secured to said plate and extending over the outer end of said pipe, said plate and member forming a chamber and material adapted to absorb moisture from the air located in said chamber in the path of air entering or leaving the outer end of said pipe.

9. The combination with a plate a pipe extending therethrough and secured to said plate, a dome shaped member secured to the outer edge of said plate and covering one end of said pipe there being an annular space between the outer edge of said plate and said dome shaped member, said plate member and pipe forming a chamber and absorbent material located in said chamber.

ROBERT V. BINGAY.
